UNITED STATES PATENT OFFICE.

SAMUEL RUTTENBERG AND MEYER NATHAN LEIBOWITZ, OF BROOKLYN, NEW YORK.

DESIGN FOR A RADIO DIAL.

Application filed September 11, 1925. Serial No. 14,760. Term of patent 7 years.

To all whom it may concern:

Be it known that we, SAMUEL RUTTENBERG, a citizen of the United States, residing at 945 Park Place, borough of Brooklyn, in the county of Kings and State of New York, and MEYER NATHAN LEIBOWITZ, a citizen of the United States, residing at 263 Eastern Parkway, borough of Brooklyn, in the county of Kings and State of New York, have invented a new, original, and ornamental Design for a Radio Dial, of which the fol-

lowing is a specification, reference being had to accompanying drawings, forming part thereof.

The figure is a plan view of a radio dial, showing my new design.

I claim:

The ornamental design for a radio dial, as shown.

SAMUEL RUTTENBERG.
MEYER NATHAN LEIBOWITZ.
